Filed Aug. 24, 1971, Ser. No. 174,578

Term of patent 14 years

Int. Cl. D3—99

U.S. Cl. D87—1 R

FIG. 1

FIG. 3

FIG. 2

FIG. 4

FIG. 1 is a front elevational view of a sport ball bag showing my new design;

FIG. 2 is a side elevational view thereof;

FIG. 3 is a rear elevational view; and

FIG. 4 is a perspective view showing another embodiment of my new design.

The design is characterized by the inverted V shaped slope of the back wall of the sport ball bag in combination with the relatively wide centrally positioned strap.

I claim:

The ornamental design for a sport ball bag, as shown and described.
